COMBINED BABY BOTTLE HOLDER AND RING EXERCISER

Thomas J. Horner, 6205 W. 77th St.,
Prairie Village, Kans.

Filed Oct. 5, 1964, Ser. No. 82,024

Term of patent 3½ years

(Cl. D83—8)

FIG. 1 is a perspective view of a combined baby bottle holder and ring exerciser showing my new design;

FIG. 2 is a perspective view thereof with the ring members in an alternate position;

FIG. 3 is a top plan view thereof;

FIG. 4 is a side elevational view thereof; and

FIG. 5 is a fragmentary elevational view as seen from the rear of FIG. 1.

The broken lines are shown for illustrative purposes only.

I claim:

The ornamental design for a combined baby bottle holder and ring exerciser, as shown and described.
